COMBINED PACKAGING CONTAINER AND STAND THEREFOR

Randall M. Budd, 541 W. Commerce,
Dallas, Tex. 75208

Filed Mar. 28, 1973, Ser. No. 345,657

Term of patent 14 years

Int. Cl. D9—03

U.S. Cl. D9—182

FIG. 1

FIG. 2

FIG. 3

FIG. 4

FIG. 5

FIG. 1 is a front elevational view of a combined packaging container and stand therefor showing my new design;

FIG. 2 is a left side elevational view;

FIG. 3 is a reduced scale perspective view;

FIG. 4 is a left side elevational view of a modified form of the combined packaging container and stand therefor; and

FIG. 5 is a left side elevational view of a further modification of the combined packaging container and stand therefor.

I claim:

The ornamental design for a combined packaging container and stand therefor, as shown and described.
